UNITED STATES PATENT OFFICE.

FRANK L. O. WADSWORTH, OF WILLIAMS BAY, WISCONSIN, ASSIGNOR TO
WILLIAM A. BOND, TRUSTEE, OF CHICAGO, ILLINOIS.

PANEL AND TILE THEREFOR.

SPECIFICATION forming part of Letters Patent No. 640,841, dated January 9, 1900.

Application filed April 13, 1898. Serial No. 677,486. (No model.)

To all whom it may concern:

Be it known that I, FRANK L. O. WADSWORTH, a citizen of the United States, residing at Williams Bay, in the county of Walworth and State of Wisconsin, have invented 5 certain new and useful Improvements in Panels and Tiles Therefor, of which the following is a specification.

My invention relates to tiles, either transparent or opaque and which are to be assembled in a panel; and my invention consists of so constructing the same and in so combining material that a strong and rigid panel is secured with no joints permitting of the passage of water, as fully set forth hereinafter and as illustrated in the accompanying drawings, in which—

Figures 1 and 10 are plan views of tiles of different forms embodying my improvements. 20 Fig. 2 represents the tiles assembled in a panel. Figs. 3 to 9 represent in section the adjoining edges of tiles with intervening filling material, the ribs, and recesses of different forms.

The tiles N may be of any suitable shape, material, and proportions, but as shown are rectangular, all but those illustrated in the last two figures being prismatic tiles. Each tile has upon some of the edges longitudinal 25 ribs or projections 1, and at the remaining edges grooves 2 corresponding in form to the ribs 1, so that when a series of tiles is assembled, as in Fig. 2, the ribs of one tile will extend into the grooves of the adjacent tiles.

In building up illuminating and other structures, however, it is not only necessary to secure a bearing of one tile upon another, but it is further essential that the parts shall be fixed and relatively immovable and also that 30 the joints shall be waterproof. To secure these results, the ribs are not of a size to exactly fit and fill the grooves, but are somewhat smaller or so constructed that when the panels are slightly separated there will be a narrow space between the opposing edges of the tiles. This space is filled with any suitable 45 filling material, as cement, amalgam, or metal cast or electrodeposited on the edges, which in this case must be first metalized or coated

with conducting material. The ribs, while 50 they do not exactly fit the grooves, extend into the same so as to bear within the grooves on the filling material therein, whereby one tile is transversely supported by those adjacent, while the filling material, when of metal 55 in one homogeneous piece, serves to bind and hold all the parts immovably together and to constitute, with the tiles, a rigid structure of great strength, the depression of any tile simply compressing the filling material and having no tendency to shear it. To further unite the parts and lock them against independent lateral displacement or separation, the ribs may be larger at their outer portions and the grooves dovetailed, as illustrated in Figs. 8 60 and 9, the filling material in such case constituting a key, which, unless crushed or broken, effectually prevents the withdrawal of the rib from the groove.

It is in most instances essential that the tiles 70 shall be secured in a supporting-frame, and as some of the edges presented to this frame have ribs and others are grooved the frame A is provided at some of the sides with grooved strips 4 and at the other sides with strips 5, 75 adapted to enter the grooves in the tiles, the strips 4 and 5 being secured in place as shown or in any other suitable manner, and the filling extending between the edges of the tiles and the faces of the strips and flanges. Any 80 other suitable supporting-frame may be employed.

Without limiting myself to the precise construction shown or to the use of any special filling material, I claim as my invention— 85

1. A panel consisting of a series of vitreous tiles having corresponding ribs and grooves at their adjacent edges and a continuous metallic frame (cast or electrodeposited) filling the spaces between the tiles, substantially as 90 set forth.

2. A panel provided with a series of ribbed and grooved tiles arranged with the ribs of one within the recesses of others, but separated to form spaces, a surrounding frame and a filling material in said spaces and between the tiles and the frame, substantially as set forth. 95

3. A panel provided with a series of ribbed

and grooved tiles arranged with the ribs of one within the recesses of others but separated to form spaces, a surrounding frame and a metallic filling material in said spaces and between the tiles and the frame, substantially as set forth.

In testimony whereof I have signed my

name to this specification in the presence of two subscribing witnesses.

FRANK L. O. WADSWORTH.
